UNITED STATES PATENT OFFICE

93,982

DESIGN FOR AN INSTRUMENT PANEL

Manfred J. Johnson, Naugatuck, Conn.

Application March 10, 1932, Serial No. 43,144

Term of patent 7 years

To all whom it may concern:

Be it known that I, MANFRED J. JOHNSON, a citizen of the United States, residing at Naugatuck, in the county of New Haven and State of Connecticut, have invented a new, original, and ornamental Design for Instrument Panel, of which the following is a specification, reference being had to the accompanying drawing, forming part thereof.

Figure 1 is a plan view of the instrument panel showing my new design.

Fig. 2 is a side view of the panel, partly in section, showing the rises and falls in the surface thereof.

In this view, the knob has been omitted.

I claim:

The ornamental design for an instrument panel, as shown.

MANFRED J. JOHNSON.
